UNITED STATES PATENT OFFICE.

JOHN KNITTEL, OF ALLEGHENY, PENNSYLVANIA.

DUMPING-CAR.

No. 821,808.

Specification of Letters Patent.

Patented May 29, 1906.

Application filed January 29, 1906. Serial No. 298,481.

To all whom it may concern:

Be it known that I, JOHN KNITTEL, a resident of Allegheny, in the county of Allegheny and State of Pennsylvania, have invented certain new and useful Improvements in Dumping-Cars; and I do hereby declare the following to be a full, clear, and exact description of the invention, such as will enable others skilled in the art to which it applies to make and use the same.

My invention relates to improvements in dumping-cars, the object of the invention being to provide an improved dumping-car in which a single operator can tilt the car body to any angle to partially or entirely dump the contents thereof and in which the body will be locked against movement at any and all positions.

A further object is to provide improved means for releasing the body to permit it to return to normal position and provide a brake to govern the return movement of the body.

With these and other objects in view the invention consists in certain novel features of construction and combinations and arrangements of parts, as will be more fully herein-after described, and pointed out in the claims.

In the accompanying drawings, Figure 1 is a view in side elevation, illustrating my improvements. Fig. 2 is an end view, and Figs. 3 and 4 are enlarged views of details of construction.

1 represents a car-platform supported on wheeled trucks 2 and having uprights or standards 3 secured thereon near its respective ends.

4 represents my improved car-body, which is preferably of substantially semicylindrical form, preferably flared at its top and provided with concentric trunnions 5 at its ends supported in bearings at the top of standards 3. Curved worm-racks 6 are located on the car-body 4 at its respective ends and are normally in mesh with worms 7, the latter being secured upon shafts 8, mounted in eccentric bearings 9, and said bearings are provided with arms 10. The arms 10 are connected by links 11 with the arms 12 of crank-shafts, and other arms 13 of said crank-shafts are connected together by a link 14 and to a lever 15 by a link 16, so that when said lever is moved the eccentric bearings will be turned to move the worms 7 into or out of mesh with racks 6. Lever 15 is provided with a detent 17 to engage a notched

segment 18 and lock the lever in any position.

On a standard 3 at one end of the car an approximately vertical shaft 19 is supported and provided at its upper end with a hand-wheel 20 to turn the same. This shaft 19 has a beveled gear 21 at its lower end meshing with a similar gear 21^a on a cross-shaft 21^b, and the latter carried a pinion 22 at one end meshing with a gear 23 on a shaft 8. The other end of this shaft 8 has a beveled gear 24 meshing with a similar gear 25 on a longitudinal shaft 26, connected by beveled gears 27 and 28 with the other shaft 8, so that both shafts will be turned simultaneously when hand-wheel 20 is turned. By turning shafts 8 worms 7, meshing with racks 6, will cause the body 4 to tilt, and the contents of the body can be entirely or partially dumped as desired, the worms serving to lock the body at any and all positions. To permit a rapid return of the body to its normal position, lever 15 may be operated to throw the worms out of mesh with racks 6, when the body will swing back to normal position by gravity, and to prevent a too rapid movement of the body a brake 29 is provided to engage the body and restrict its momentum by frictional contact. This brake is controlled by a lever 30 at one end of the car, and the entire operating mechanism is therefore located at one end of the car in easy reach of an operator, who, single-handed, can operate the car.

Slight changes might be made in the general form and arrangement of the parts described without departing from my invention, and hence I would have it understood that I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. In a dumping-car, the combination with a transversely-curved body having a curved closed bottom, and means for pivotally supporting the same, of a curved rack secured directly to said curved bottom of the body and means under the body engaging the rack for tilting said body.

2. In a dumping-car, the combination with a pivotally-supported body and a series of worm-racks thereon, worms engaging said racks, operating means for each rack, and

devices connecting said operating means, whereby all of said operating means can be actuated simultaneously by a single operator at one end of the car.

5 3. In a dumping-car, the combination with a pivotally-supported body, and a rack thereon, of operating means for the rack and means for moving the operating means into and out of engagement with the rack.

10 4. In a dumping-car, the combination with a pivotally-supported body, and a series of racks thereon, of a series of operating means for the racks, and means for moving all of said operating means, simultaneously into or

15 out of engagement with the racks.

5 5. In a dumping-car, the combination with a pivotally-supported body and a series of worm-racks secured thereto, of worms for actuating said racks to turn the body and

20 means for raising said worms into mesh with

said racks or lowering them therefrom.

25 6. In a dumping-car, the combination with a pivotally-supported body, of actuating means for tilting the body, means for throwing said actuating means out of gear, whereby the body will be permitted by gravity to return to its normal position, and a brake for controlling such return movement.

30 7. In a dumping-car, the combination of a semicylindrical car-body pivotally supported at its ends, worm-racks around the body, worms meshing with the racks, means for turning the worms, and means for moving the worms out of mesh with the racks and

35 into mesh therewith.

30 8. In a dumping-car, the combination of a

semicylindrical body pivotally supported at its ends, worm-racks around the body at both ends, worms meshing with the racks, shafts supporting the worms, eccentric bearings for said shafts, means for turning the shafts simultaneously, and means for turning the eccentric bearings to move the worms into or out of mesh with the racks.

40 9. In a dumping-car, the combination of a semicylindrical body pivotally supported at its ends, worm-racks on the body, worms meshing with the racks, means for turning the worms to tilt the body, means for throwing the worms out of mesh with the racks, and a brake engaging the body to govern the momentum of the return movement of the body to normal position.

45 10. In a dumping-car, the combination with a car-platform, standards thereon, a semicylindrical body, and trunnions on the ends of the body supported in the standards, of worm-racks on the body, worms meshing therewith, means at one end of the car to turn the worms, a lever at the same end of the car to throw the worms out of mesh with the racks, and a brake-lever at this same end of the car to control the momentum of the body in its return movement.

50 In testimony whereof I have signed this specification in the presence of two subscribing witnesses.

JOHN KNITTEL.
